UNITED STATES PATENT OFFICE.

OTTO BANNER, OF EASTON, PENNSYLVANIA, ASSIGNOR TO INGERSOLL-RAND COMPANY, OF NEW YORK, N. Y., A CORPORATION OF NEW JERSEY.

TURBINE.

1,090,443.

Specification of Letters Patent. Patented Mar. 17, 1914.

Application filed December 27, 1911. Serial No. 668,035.

To all whom it may concern:

Be it known that I, OTTO BANNER, a subject of the German Emperor, and resident of Easton, in the county of Northampton and 5 State of Pennsylvania, have invented a new and useful Improvement in Turbine-Engines, of which the following is a specification.

This invention consists of a double flow mixed pressure turbine engine of the so-called action or velocity type, in which the shaft may be driven by high pressure or low pressure motive fluid or by a combination of the two, the fluid passing through the two low pressure elements in opposite directions 15 and the arrangement being such that one of the low pressure elements and the high pressure element may run idly if so desired.

Practical embodiments of my invention are represented in the accompanying drawings, in which—

Figure 1 is a view of the turbine engine half in side elevation and half in longitudinal central vertical section showing one form of the invention, Fig. 2 is a detail section 25 showing a modified form of the high pressure element, and Fig. 3 is a detail section showing a third form of the high pressure element.

The shaft is denoted by 1, the low pressure blade wheels by 2 and the high pressure blade wheels by 3. Each low pressure wheel 2 is shown as provided with a single row of blades 4 and each high pressure wheel 3 is shown as provided with a single row of blades 5.

The partitions in the low pressure elements are denoted by 6 and their nozzles by 7. The partitions in the high pressure element are denoted by 8 and their nozzles by 9. At one end of the casing I provide an inlet chamber 10 communicating with the low pressure inlet 11 and at the other end of the casing I provide an inlet chamber 12 communicating with the high pressure inlet 13.

A common intermediate chamber 14 is provided, which chamber communicates with the outlet 15. A chamber 16 is formed in the casing intermediate the high pressure chamber 12 and the common outlet chamber 14, which chamber 16 communicates with the low pressure inlet 17 and is also arranged to receive the streaming fluid which passes from the high pressure chamber 12 through the nozzles and blades of the high pressure element.

The casing, as shown in Fig. 1, is divided transversely vertically into end members, cylinder members and an intermediate divided ring member. The casing is also divided in a horizontal plane co-incident 60 with the axis of the shaft 1 to form the upper and lower half sections 18, 19, and 20, 21, of the cylinder members of the casing, the upper and lower half members 22, 23, and 24, 25, of the end members of the casing and 65 the upper and lower divided half sections 26, 27, and 28, 29, of the intermediate ring member. The lower half sections 19 and 21 of the cylinder members may be provided with brackets 30, 31, for use in supporting the 70 engine.

Valves 32, 33, 34, serve to independently control the admission of the motive fluid to the low pressure chamber 10, high pressure chamber 12 and intermediate low pressure 75 chamber 16.

The bearings for the shaft 1 at the opposite ends of the casing may be divided in a horizontal plane co-incident with the axis of the shaft 1 to form upper and lower half 80 sections 35, 36, and 37, 38.

I have shown the two low pressure elements as each comprising four stages and have shown single rows of blades. It is to be understood, however, that the number of stages 85 and the number of rows of blades may be varied to suit different requirements.

In Fig. 1, I have shown the high pressure element as comprising two blade wheels and two partitions having single rows of blades 90 and nozzles.

In Fig. 2, I have shown a single blade wheel having two rows of blades 39, 40, with an interposed row of fixed blades 41.

In Fig. 3 I have shown a single high pressure wheel with a single row of blades of greater blading diameter than the rows of blades in the low pressure elements and have shown the portion of the casing which includes the high pressure element as detachable 95 from the portion of the casing which includes the low pressure elements.

These modifications are simply shown as examples of many different ways in which the elements may be arranged without departing from the spirit and scope of my invention.

The parts are so arranged that the shaft may be turned by the use of the high pressure element alone, by the use of either one 110

of the low pressure elements alone or by the use of any combination of the three elements as may be required.

What I claim is:—

- 5 1. A mixed pressure turbine engine including a casing divided transversely vertically into a low pressure element member, a combined high and low pressure element member and an intermediate outlet member.
- 10 2. A mixed pressure turbine engine including a casing having high and low pressure element members and divided transversely vertically into end inlet members and an intermediate outlet member.
- 15 3. A mixed pressure turbine engine including a casing divided transversely vertically into end members, cylinder members and an intermediate ring member, one end member containing a low pressure inlet chamber, the other member containing a high pressure inlet chamber, the ring member containing the outlet chamber, and one of the cylinder members containing a low pressure inlet chamber intermediate the high pressure inlet chamber and the outlet chamber.
- 20 4. A mixed pressure turbine engine including a casing divided transversely vertically into end members, cylinder members and a divided ring member, one end member containing a low pressure inlet chamber, the other end member containing a high pressure inlet chamber, the divided ring member containing the outlet chamber and one of the cylinder members containing a low pressure inlet chamber interposed between the high pressure inlet chamber and the outlet chamber.
- 25 5. A mixed pressure turbine engine in-

cluding a casing having high and low pressure element members and divided horizontally into upper and lower half sections and transversely vertically into end inlet members and an intermediate outlet member.

6. A mixed pressure turbine engine including a casing divided horizontally into upper and lower half sections and transversely vertically into end members, cylinder members and an intermediate ring member, one end member containing a low pressure inlet chamber, the other inlet member containing a high pressure inlet chamber, the ring member containing the outlet chamber and one of the cylinder members containing a low pressure inlet chamber between the high pressure inlet chamber and the outlet chamber.

7. A mixed pressure turbine engine including a casing divided horizontally into upper and lower half sections and transversely vertically into end members, cylinder members and a divided intermediate ring member, one end member containing a low pressure inlet chamber, the other end inlet member containing a high pressure inlet chamber, the ring member containing the outlet chamber and one of the cylinder members containing a low pressure inlet chamber between the high pressure inlet chamber and the outlet chamber.

In testimony, that I claim the foregoing as my invention, I have signed my name in presence of two witnesses, this 23d day of Dec. 1911.

OTTO BANNER.
